FRANK N. WILCOX.

UNITED STATES PATENT OFFICE.

JOHN L. POPE, OF CLEVELAND, OHIO.

DESIGN FOR A WRENCH.

SPECIFICATION forming part of Design No. 13,435, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and original Design for S-Wrenches, of which the following is a specification, reference being had to the accompanying engraving, forming part thereof.

My present invention relates to a design for "S-wrenches;" and it consists in certain features of ornamentation, which will be hereinafter more fully described, and particularly pointed out in the claims.

In the accompanying engraving I have shown what is known in the market as a "multiple S-wrench"—that is to say, an S-wrench provided at each end with a number of differently sized jaws.

The wrench illustrated has three jaws at each end of the handle, which construction, I am aware, is not novel; but I have ornamented the jaw ends of the implement, and in that particular lies my improvement. As will be seen in the engraving, each extremity of the wrench, though differing in size, is of substantially the same configuration, and has two triangularly-shaped portions, A A. These I have

adorned by forming therein sunken or depressed portions *a a*, substantially triangular in shape. At that end of the wrench at which are located the large jaws (the lower end in the engraving) I have ornamented the body of the metal between the jaws by producing an oblong depression, *b*, forming ribs *c* on each side, from which extend at right angles branch ribs *d* until the outer bead or edge of the wrench is reached. At the other end of the wrench are ornamental ribs or bars, which will be found designated by the letter *e*, and which, it will be observed, are a little differently disposed.

What I claim as new, and desire to secure by Design Letters Patent, is—

1. An S-wrench ornamented substantially as shown and described.

2. A wrench having the triangular-shaped extremities provided with depressed or sunken portions, substantially as shown and described.

In witness whereof I have hereunto set my hand this 17th day of July, 1882.

JOHN L. POPE.

In presence of—

L. S. FISH,

FRANK N. WILCOX.
